Patented June 18, 1963

195,481

SPACING UNIT FOR A GRILLE

Edward C. Hallock, 86 Woodland Ave., Summit, N.J.

Filed Apr. 29, 1960, Ser. No. 60,383

Term of patent 14 years

(Cl. D54—2)

FIG.2.

I claim:

The ornamental design for a spacing unit for a grille, as shown.
